APPARATUS FOR FEEDING FILLER THREAD TO KNITTING MACHINES

Ferdinand Klumpp, Union City, and Charles H. Colvin, Morristown, N. J., assignors, by mesne assignments, to Robert Reiner, Incorporated, Weehawken, N. J., a corporation of New Jersey

Application June 10, 1939, Serial No. 278,392

14 Claims. (Cl. 66—84)

This invention relates to apparatus for manufacturing fabrics, and more particularly to mechanism for supplying yarn to a knitting machine preferably of the type generally referred to as a warp machine.

One of the objects of this invention is to provide fabric manufacturing apparatus capable of forming a knitted fabric with or without a filler form threads or yarns of various kinds of material. Another object is to provide, in a warp knitting machine or the like, mechanism for feeding various kinds of warp and filler threads to the knitting instrumentalities in such a manner that the threads are in a proper predetermined condition of tautness as they are formed into the fabric. Another object is to provide warp and filler feed mechanism for a warp machine or the like which is practical and efficient in operation and which is automatically responsive to a condition of the warp and filler. Other objects will be in part apparent and in part pointed out hereinafter.

The invention accordingly consists in the features of construction, combinations of elements and arrangements of parts as will be exemplified in the structure to be hereinafter described, and the scope of the application of which will be indicated in the following claims. In this connection it is mentioned that the appended claims are directed to the subject matter of the apparatus for feeding filler thread to a knitting machine, and that the apparatus for feeding warp thread to a knitting machine is covered by the claims of applicants' continuation in part application Serial #470,540, filed December 30, 1942.

In the drawings, in which is shown one of the various possible embodiments of our invention,

Figure 1 is an elevation, partly in section, of a warp machine having our warp and filler feed mechanism associated therewith, a portion of the warp machine being broken away;

Figure 2 is a fragmentary top plan view of our warp feed mechanism;

Figure 3 is a fragmentary front elevation of our warp feed mechanism;

Figure 4 is a fragmentary elevation of our filler feed mechanism; and

Figure 5 is a fragmentary elevation of a portion of our warp feed mechanism illustrating a mercury switch controlled by a balanced member of the mechanism.

Flat knitting machines, for example, warp machines, in many instances employ warp beams on which are wound a desired number of warp threads or ends which are drawn from the beam as they are knitted into fabric by the needles of the machine. As these threads are knitted, the beam revolves, and in most instances it is necessary to provide some sort of a beam brake to prevent the beam from running free and per-

mitting a loose or slack condition of the warp thread at the knitting needles. Various types of friction brakes have been devised for preventing free rotation of the beams, but have met with 5 indifferent success because they are inherently incapable of permitting rotation of the beam at the time and in the amount required. If the friction device has a sufficient braking action on the beam to prevent the beam from overrunning because of its momentum, the pull of the warp threads necessary to turn the beam initially against the friction of the brake places the threads under greater tension than is usually desired, this being particularly so in the case 10 of highly elastic yarns such as certain worsted yarns and lastex yarns.

In the case of elastic threads, such as lastex yarn, it is practically impossible with friction brakes to control the feed of the yarn in such 15 a way that it is under a substantially constant tension. This lack of control often results in a fabric of uneven texture with promiscuously scalloped edges. In the case of loosely spun yarns, such as fine gauge loosely spun worsted yarns of 20 slight tensile strength, a friction brake device for controlling beam rotation is practically useless and sometimes harmful. Furthermore, the weight of the beam is often so substantial that the force necessary to overcome its inertia is 25 greater than the combined tensile strength of the threads which pull upon the beam, with the result that the threads part. This condition is particularly evident in the manufacture of narrow fabrics where the total warp ends are relatively few in relation to the size and weight of 30 the beam. Still other types of warp threads such as, for example, asbestos, have practically no tensile strength at all and cannot properly be formed into a fabric if they are slack at the needles. It will be apparent that under such 35 conditions a friction brake for the beam would actually be disadvantageous and a free running beam would not solve the problem.

In the manufacture of metal fabrics, such as 40 are used for example for commercial filters, etc., different kinds of metallic threads are formed into cloth. Such threads in most cases have slight elasticity but substantial tensile strength, and, to form a metal cloth of even texture, should 45 be in an unslackened condition when operated on by the knitting needles. If such wire threads are under substantial tension there is considerable risk of needle breakage by reason of the relative inflexibility of the metal. In some cases, 50 a certain amount of slack is required in the metal warp threads where certain types of metal cloth are being made. Either condition of the metal thread is difficult, if not impossible to obtain 55 with the conventional frictionally restrained beam.

Often the above-noted fabrics, in addition to others, require the incorporation therein of filler threads. Here again it is desired to control accurately the tension of such threads as they are incorporated into the fabric, regardless of the texture of the threads or their tensile strength. In so far as we have been able to determine, there has been no satisfactory solution of the problems encountered in properly tensioning such filler threads as desired in different types and kinds of fabrics. Often but a single strand is incorporated as a filler, and where the thread being used has slight tensile strength, it is clear that the forces exerted on the thread by the pull of the machine must be accommodated or counteracted in order to avoid breakage. Where an elastic filler is being incorporated into the fabric, it is often desirable to maintain the tension of the thread at a predetermined, constant value, and for the reasons pointed out hereinabove, conventional friction brake devices are unsatisfactory.

It is accordingly another object of this invention to obviate the above-mentioned difficulties, and to provide warp and filler feeding mechanism which solves the several problems referred to in a thoroughly efficient and practical manner.

Referring now to Figure 1 of the drawings, a knitting machine is generally indicated at 10, and this machine may be similar to that shown in the copending application of Ferdinand Klumpp and Fritz Lambach, Serial No. 159,642, filed August 18, 1937, which has matured into Patent #2,247,092 on June 24, 1941. Machine 10, which corresponds generally to that type of knitting machine generally referred to as a warp machine, comprises suitable frames 11 and 12 rising from a base 13 which with the frame supports the operating mechanism of the machine substantially as described in detail in the aforementioned copending application. Machine 10 also includes knitting instrumentalities which in general comprise one or more needle banks, a plurality of longitudinally arranged sinkers 15 and cooperating sets of loopers 16. Needles 14, sinkers 15 and loopers 16 coact upon operation of the machine to knit thread or yarn supplied thereto into a fabric which, if desired, may have incorporated therein a filler through the operation of a carrier or filler laying mechanism 17. If desired, a complete description of these several instrumentalities may be found in the above-noted copending application.

Frames 11 and 12 support a suitable number of arms 18 and 19 which in turn support posts or uprights 20 and 21. These posts have mounted thereon suitable hangers or brackets 22 disposed at opposite ends of the machine and between which supporting tubes 23 extend. Any suitable number of supporting tubes 23 may be provided, but for illustrative purposes we have chosen to show a pair at the left-hand side or front of the machine, as viewed in Figure 1, and a pair at the rear of the machine. Tubes 23 therefore comprise suitable supports for pairs of notched bars 24 and 25, these bars being located at opposite ends of the machine to provide suitable beam supports.

The yarn or thread knitted in a knitting machine of the type under consideration is usually wound in suitable lengths on a beam, and as the yarn is knitted into fabric by the machine, it is drawn from the beam effecting rotation thereof. Such a beam (see the top of Figure 1) is

indicated at 26 and is supported on upper beam supports 24, being maintained against displacement by notches 24a in upper supports 24. Beam 26 has a suitable supply of warp yarn or thread W. As noted hereinabove, conventional beam rotation controls usually take the form of a friction brake or the like which prevents free running of the beam. As noted, however, there are many disadvantages to this type of beam control, and to the preclusion thereof we have provided the mechanism now to be described.

As shown in Figure 1, the upper left-hand tube support 23 has mounted thereon a discoid plate 27, the upper portion 27a of which (see Figures 2 and 3) carries an electric motor 28. The upper end of the motor housing has attached thereto a casing 29 which contains suitable speed reduction gears connected to a pinion 30 which meshes with a gear 31 (Figures 1 and 2) mounted on the axle or spindle 26a of beam 26. Operation of motor 28, as will be described in detail hereinafter, thus effects rotation of beam 26 through the action of gears 30 and 31, but because of the speed reduction afforded by the gears in housing 29, beam 26 is rotated at suitably slow speed.

As shown in Figures 2 and 3, a pair of brackets 33 and 34 are suitably mounted on upper tubular support 23, and as is more clearly shown in Figure 1, the upper surfaces of these brackets are inclined with respect to the horizontal, and are provided with a series of notches 33a and 34a (Figure 3) respectively. A drum or roller 35 is suitably supported on a spindle 36, and the opposite ends of the spindle are carried in corresponding notches 33a and 34a of supports 33 and 34.

As shown in Figure 3, lower beam supporting bars 25 have depending therefrom a pair of hangers 37 and 38, the upper portions 37a and 38a of these hangers adjustably embracing bars 25 so as to be movable longitudinally of the bars, as viewed in Figure 1. At the lower ends of hangers 37 and 38 we provide pivot blocks 39 and 40 suitably pivoted to the hangers and adapted to adjustably receive respectively frame bars 41 and 42, the left-hand ends of which, as viewed in Figure 2, are connected by a rod 43 or the like. The opposite ends of bars 41 and 42 are also connected by a rod 44, and between rods 43 and 44 we provide a tension bar or roller 45, the opposite ends of which are supported or journaled in rods 41 and 42 (see Figure 3). As shown in Figures 1 and 2, rod 44 carries a depending weight 46, the mass of which may be varied in accordance with the tension desired to be imparted to warp W as will be described below.

Referring to the upper left-hand portion of Figure 1, the warp threads W are taken from beam 26, led beneath tension bar 45, passed over roller 35 and thence trained downwardly across a guide 47 suitably secured to machine 10 and finally through loopers 16 to needles 14. It may now be seen that by reason of the warp threads W passing under tension roller 45 frame bars 41 and 42 together with tension roller 45, rod 44 and weight 46 comprise a balance member having opposed forces acting thereon, i. e., the upward pull of warp threads W and the downward force exerted by weight 46. It will also be clear that the force exerted by weight 46, and hence the tension on warp threads W, may be varied as desired either by varying the distance between tension roller 45 and pivot blocks 39 and 40, or by varying weight 46.

As best seen in Figure 5, motor 28 is connected in circuit with a mercury switch 48, which is supported in a cradle 49 mounted on the upper end 31a of hangers 37. Cradle 49 includes a downwardly extending arm 50 from which extends a stud 51 which is received in a fork 52 secured to the end of a rod 53, the lower end of rod 53 being fixed to pivot block 39 (see Figure 3). As rod 53 is related to frame bars 41 and 42 at the pivotal axis thereof, slight angular movement of the bars effects substantial angular displacement of fork 52. Thus, as viewed in Figure 5, clockwise movement of rod 53 and fork 52 causes counter-clockwise movement of switch 48 causing the mercury therein to flow away from switch contacts 48a and 48b to break the circuit to motor 28. Similarly, counter-clockwise movement of rod 53 causes clockwise movement of mercury switch 48 to close the circuit to the motor.

From the above, it will now be clear that as warp threads W (Figure 1) are drawn into machine 10 by the action of the knitting instrumentalities therein, the threads pull against tension roller 45 to cause counter-clockwise movement of frame bars 41 and 42. As hereinbefore noted, this effects clockwise movement of mercury switch 48 to energize motor 28. Energization of the motor causes rotation of beam 26, and thus warp thread is positively fed by the beam, which precludes an increase in thread tension. Feeding of the warp thread, however, by motor 28, eases the pull of the warp threads and thus permits tension roller 45 and the associated frame bars 41 and 42 to drop, i. e., the frame bars move clockwise. This effects counter-clockwise movement of mercury switch 48, which breaks the circuit to motor 28 and feeding of warp by beam 26 ceases. Thus, for but slight increases or decreases in the tension of the warp threads W, beam 26 is operated or its rotation is stopped, and in effect the tension of the warp threads is maintained at a substantially constant value.

While we have shown but one warp beam and but a single control therefor, it will be obvious that a plurality of beams and controls may be used to supply as many sets of warp threads as are desired up to practical limitations. It will also be clear from the above that regardless of the type of warp thread being used, its tension or lack of tension can be readily and closely controlled so that in the case of elastic warp threads, such threads can be knitted while under tension so as to result in an elastic fabric. Where warp threads of little or no tensile strength are being knitted, there is no danger of the threads being torn by reason of the pull exerted thereon by the knitting action, as the threads can be positively fed through the action of motor 28, as described. Similarly, where a metal cloth is being manufactured, and it is desired to maintain the metal warp threads under high tension, this substantial tension can readily be maintained by the control herein described where it would be difficult if not impossible to do so with a conventional friction beam brake.

As hereinbefore noted, it is often desirable to incorporate a filler thread or threads into the fabric as it is being knitted. To this end, we have provided the filler feed mechanism generally indicated at 54 (left-hand side of Figure 1). Filler feed mechanism 54 comprises a standard or support 55 which carries a lower platform 56 and an upper support 57. As is more clearly shown

in Figure 4, a spindle 58 has its inner end rotatably mounted in platform 57, the spindle extending from the platform so as to support a spool 59 of filler thread F. Spindle 58 also carries a spur gear 60 which meshes with a gear 61 adapted to be driven by a motor 62 through speed reduction mechanism 63. Thus, as gears 61 and 60 are operated by the motor, spool 59 is rotated as a suitable rate of speed to unwind filler thread F therefrom.

Filler thread F is led through an eye 64 carried by arm 65 suitably secured to support 55, and from this eye it is passed through another eye 66 secured to the top of a weighted shutter 67. Shutter 67 is provided with guide arms 68 which embrace vertical guide posts 69 and 69a (Figure 1) which constrain the weighted shutter to movement in a vertical plane, as will be described.

Platform 56 includes an extension 56a on which a source of light 70 is mounted. Lighting device 70 is arranged and adapted to cast a beam B of light in the direction of a photoelectric cell 71, which is connected in a conventional manner to a suitable switch generally indicated at 72, switch 72, in turn, being connected to motor 62 to effect energization and deenergization thereof as the beam B falls on photocell 71, or is cut off therefrom by shutter 67.

It will thus appear that weighted shutter 67 is the controlling factor of the feed of filler thread F.

From eye 66 on weighted shutter 67 filler thread F is led through another eye 73 in arm 65 (Figure 1) and from this eye the filler thread leads to suitable eyes on carrier 17, which reciprocates, as described in the above-mentioned copending application of Klumpp and Lambach, to lay the filler in the fabric as it is knitted. As the carrier 17 reciprocates, it draws filler thread F into machine 10 with the result that weighted shutter 67, which hangs on a loop of the filler, is pulled upwardly along guide rods 69 and 69a. However, as soon as the shutter rises sufficiently so that beam B from light source 70 can fall on photocell 71, motor 63 is energized to cause rotation of filler spool 59. This effects a positive feed of filler thread F, and therefore there is no tension created in the filler by the reciprocation of carrier 17 other than that resulting from the weight of weighted shutter 67. If but little tension is desired in filler thread F, the weight of shutter 67 may be adjusted accordingly. If substantial tension in the filler thread is desired, it is obvious that the attainment thereof is readily effected by increasing the weight of the shutter. In any event, the value of the tension under which filler thread F is drawn into the machine is maintained substantially constant, which assures an evenly textured fabric free from a ruffled or scalloped effect. It will be clear that this condition will obtain regardless of the nature of the filler thread, and it also will appear that by reason of the positive feed of filler thread, a thread of very low tensile strength may be used without risk of the threads parting.

Thus we have provided automatic feed for both warp and filler threads of such a nature that regardless of the kind of thread or yarn being used, the tension under which it is being fabricated may be maintained at a predetermined constant value with the result that an evenly textured fabric is readily attainable. Furthermore, by reason of the positive feed effected by our warp and filler feed devices, warp and filler threads of extremely low tensile strength may be fabricated

to form a fabric of a fineness heretofore unattainable in a machine of this character. As substantial flexibility of adjustment is afforded by our controls, elastic yarns may readily be fabricated to form fabrics of substantially any desired elasticity up to the elastic limits of the threads employed.

Accordingly in the provision of the above-described apparatus, we have attained the various objects hereinbefore described in a thoroughly practical and efficient manner.

As many possible embodiments may be made of the above invention and as many changes might be made in the embodiment above set forth, it is to be understood that all matter hereinbefore set forth, as shown in the accompanying drawings is to be interpreted as illustrative and not in a limiting sense.

We claim:

1. Apparatus for feeding filler thread to a knitting machine or the like comprising, in combination, a spool, means including an electric motor for driving said spool, means for tensioning the thread as it is fed from said spool, and means responsive to a variation in the tension of said thread for affecting the operative condition of said electric motor.

2. Filler feeding mechanism for knitting machines and the like comprising a supply of filler thread, power means for taking off thread from said supply, a loop formed in said thread, a shutter hung on said loop, and electrical means including a light sensitive cell controlled by said shutter for operating said power means to remove thread from the supply as said filler is consumed.

3. Filler feeding mechanism for knitting machines and the like comprising a supply of filler thread, and means for feeding thread from said supply to the machine, said means comprising a shutter hung on a loop formed by said thread, electrical means including a light sensitive cell controlled by said shutter, and means operable by said electrical means for unwinding thread from the mentioned supply.

4. In combination, a knitting machine or the like having means for incorporating filler into a fabric knitted thereby, and means for supplying filler to said machine, said means comprising filler feeding means, electrical means including a light sensitive cell for operating said filler feeding means, and a member hung on a loop formed in the thread extending between the filler feeding means and the machine for controlling said electrical means.

5. A filler feeding device comprising a supply of filler thread, means for driving said supply to feed thread therefrom, electrical means including an exciter lamp and a light sensitive cell, a member hung on a loop formed in said thread whereby said electrical means operates said driving means only when said member is out of the path of light of said exciter lamp.

6. A device for feeding filler to a knitting machine from a supply, comprising means for driving said supply to feed thread therefrom, electrical means including a light source and a light sensitive cell, and a member adapted to be hung on said thread, said electrical means operating said driving means only when said member is out of the path of light rays of said source.

7. A device for feeding filler to a knitting machine from a supply, comprising means for driving said supply to feed thread therefrom, electrical means including a light source and a light sensitive cell, and a member adapted to be hung on said thread, and locatable between said source and said cell, said electrical means operating said driving means only when said member is out of the path of light rays of said source.

8. A device for feeding filler to a knitting machine comprising, in combination, feeding means, electrical means including a light source and a light sensitive cell, and a member supportable by said thread and locatable between said source and said cell, said electrical means operating said feeding means only when said member is out of the path of light rays of said source.

9. A device for feeding filler to a knitting machine from a supply, comprising means for operating said supply to feed thread therefrom, electrical means including a light source and a light sensitive cell, and a member interposable between said source and said cell and adapted to be associated with said thread, said second-mentioned means being operable to actuate said operating means only when said member is out of the path of light rays of said source.

10. A device of the character described comprising filler feeding means, electrical means including a light sensitive cell for operating said filler feeding means, and a member supportable by the filler adjacent the filler feeding means for controlling said electrical means.

11. A device of the character described comprising filler feeding means, electrical means including a light sensitive cell and a light source for operating said filler feeding means, and a member supportable by the filler and interposable between said source and said cell for controlling said electrical means.

12. An apparatus for feeding filler thread to a knitting machine or the like comprising, in combination, a spool, an electromotor for rotating said spool to feed thread therefrom, means for maintaining the thread under tension, and electrical means controlled by said tensioning means for altering the operative condition of said electromotor in response to a variation in the thread tension.

13. An apparatus for feeding filler thread to a knitting machine or the like comprising, in combination, a spool, an electromotor for rotating said spool to feed thread therefrom, means for maintaining the thread under tension, and electrical means including a controlling switch in circuit with said electromotor and operatively connected with said tensioning means for altering the operative condition of said electromotor in response to a variation in the thread tension.

14. An apparatus for feeding filler thread to a knitting machine or the like comprising, in combination, a spool, an electromotor for rotating said spool to feed thread therefrom, means for maintaining the thread under tension, and electrical means including a light sensitive cell controlled by said tensioning means for altering the operative condition of said electromotor in response to a variation in the thread tension.

FERDINAND KLUMPP.
CHARLES H. COLVIN.
